UNITED STATES PATENT OFFICE.

OSCAR B. WINSTON, OF MEMPHIS, TENNESSEE.

COTTON-PICKING MACHINE.

Application filed June 22, 1921. Serial No. 479,541.

To all whom it may concern:

Be it known that I, OSCAR B. WINSTON, a citizen of the United States, residing at Memphis, in the county of Shelby and State 5 of Tennessee, have invented certain new and useful Improvements in Cotton-Picking Machines, of which the following is a full, clear, and exact description, which will enable others skilled in the art to make and 10 use the same.

My invention relates especially to a cotton picking machine which is adapted to be carried by the cotton picker or operator, and has for its object to provide a device of this 15 character which will quickly and efficiently transfer the cotton from the boll of the cotton plant to a receptacle provided for the purpose.

With this object in view, my device comprises the new and novel features herein-after more fully set out in the drawings, 20 specifications and claims.

In the drawings:

Fig. 1 is a front view of the device as it 25 looks when being carried by the operator and shows the position of the hands when holding the boll against the machine in order to allow the removal of the cotton.

Fig. 2 is a side view of the device showing the motor and fan in side elevation and 30 the picking device in section on the line II—II of Figure 3.

Fig. 3 is a front view of the picking head 35 of the machine, with the left half in section taken on the line III—III of Fig. 2.

Referring now to the drawings in which the parts are indicated by the same numeral in all the views, 1 is a casing covering an ordinary electric motor 1^a such as is used 40 in a vacuum carpet sweeper, and 2 the casing inclosing a fan 2^a similarly used—as no especial novelty is claimed for either the fan or motor, these are not shown in further detail—and hereinafter the numerals 1 and 45 2 will be used as referring to the motor and fan respectively rather than specifically to the casings enclosing the same. A wire 3 leads from the motor to a source of current not shown—such source may be a storage 50 battery carried on the back of the operator or on a light truck or may be from a stationary source not shown. 4 is the discharge outlet of the fan which leads through a short length of hose 5 to the cotton sack 6 which 55 may be of the ordinary type adapted to be dragged on the ground behind the operator.

This bag can drag from the connecting hose 5 but preferably is independently fastened to the belt 7 in any suitable manner so that no strain will come on the fan. The motor 60 1 and fan 2 are attached to a plate 8 adapted to rest against the stomach of the operator and to be firmly secured around his waist by the belt 7, and are supported on the person of the operator by the belt 7 and 65 by a supporting or carrying strap 9 which attaches to a projecting loop 10 on the fan 2 and is adapted to support the weight of the device from the shoulders of the operator.

The picking head of the device comprises 70 a housing or casing 11 having a contracted rear section 12 which preferably has a flange 13 fastened by screws 14 to the housing of the fan 2.

The front of this housing 11 is guarded 75 by a cover 15, attached by a hinge 16 to the said housing, and having a clamp or clamps 17 to hold it in place when closed. This cover is provided with two symmetrically located rectangular openings 18 each of 80 which has a plurality of oppositely disposed and parallel fingers 19 extending from two opposite sides thereof. These fingers preferably have their free ends depressed behind the plane of the cover 15 and these ends are 85 preferably separated by a space approximately equal to the spacing of the fingers themselves. 20, 20^a and 21, 21^a respectively are two pairs of brushes which are mounted on and rotated by shafts 22, 22^a. These 90 brushes have sets of bristles corresponding in number with the openings between the fingers 19. The bristles may be true bristles or if found desirable be of wood or metal. They are preferably so set in relation to each 95 other that the bristles of one brush fall opposite the space between bristles of the opposite brush. The shafts 22, 22^a, are driven by worm wheels 24, 24^a respectively and these wheels in turn are driven by a central 100 worm 25 which is mounted on the shaft 26 which is an extension of the fan shaft. This central location of the worm causes the two brushes of a pair (as 20, 20^a) to rotate in opposite directions as is desired and since the direction of rotation of the fan is fixed, and in order that the brushes may rotate inward or backward toward each other, the worm is so threaded that the worm wheels 24, 24^a are 105 rotated in the direction of the arrows and the brushes 20, 20^a, 21, 21^a are similarly rotated. The shafts 22, are preferably square

110

or hexagonal and are either turned down or provided with bushings 32 to form journals which rotate in the bearings 27. These square shafts engage square sockets in the 5 worm wheels 24, 24^a which drive them.

In the rear of the brushes 20, 20^a, 21, 21^a the inside of the housing 11 has oppositely disposed flanges 28, to which stripping combs 29 are attached by screws 30.

- 10 The action of the machine is as follows-- the carrying strap 9 is adjusted over the shoulders and around the neck, the plate 8 is adjusted and the strap 7 buckled to keep it securely in place. When so fastened it 15 will be especially noted that the movement of the machine is entirely controlled by the movement of the body of the operator and is not controlled by his hands nor does it interfere with the free use of the hands.
- 20 Having adjusted the machine on the person the cotton sack 6 is attached and preferably hooked to the belt 7, and the current wire 3 is connected to the motor 1.

25 The operator being now ready for picking, approaches the cotton plant and grasping the bolls with each hand brings them against the picking head, where the bristles on the brushes 20, 20^a, 21, 21^a engage the fiber of the cotton and forcibly remove it 30 from the boll, carrying the cotton backward through the picking head on the brush until it is stripped therefrom by the stripping combs 29. The vacuum current of the fan then sucks the cotton into the 35 fan and throws it through the discharge pipe 4 into the cotton sack 6.

40 It will again be noted that the movement of the body brings the machine into proximity to the cotton plant and possibly with a cotton boll, but that ordinarily the actual contact of the cotton with the brushes is brought about by bringing the open boll against the machine not the machine against the boll. Since both hands are free they can 45 be busied in bringing in the bolls either synchronously or alternately as the case may be. As soon as the brush engages the cotton the hand is released to secure additional bolls for picking. It is not intended that 50 the boll be detached from the stalk but should it be detached no harm is done. The fingers 19 hold back the bolls, stalks and leaves and let only the cotton through, but the grip of the brushes on the cotton hold 55 the boll until all the cotton is removed therefrom.

60 Where bolls are below the normal height of the machine on the operator's body, it is necessary to stoop over to bring the machine into proximity to them. I also find that some of the lower bolls on the plants are too low to be reached and these I detach and bring against the machine releasing them as soon as the lint is engaged by 65 the brushes, leaving the hands free to bring

additional bolls against the picker head, while the lint is being removed from those so engaged.

It will be clearly seen that greater speed can certainly be obtained where the boll is brought against the picker head than where the picker head is brought to the boll, especially since the boll can be released by the hand before the lint has entirely been removed and the hand be then free to bring an additional boll or bolls against the picker head. It will also be readily seen that often two or even more bolls may be brought against the picker head by a single movement of one hand.

70 It will be readily understood that minor details of the machine may be varied without departing from the spirit of my invention and that I do not wish to limit myself to the exact details here shown.

75 Having now fully described my invention, what I claim and desire to secure by Letters Patent in the United States is:—

80 1. In a cotton picking machine, a receptacle for the cotton, a housing; picking means, an exhaust fan for transferring the cotton from the picking means to the said receptacle, and a motor driving said picking means and fan, all within said housing; current wires leading to the said motor, and means attaching said housing means rigidly to the body of the operator whereby the direction of the machine will be controlled solely by the movement of the operator and the hands of the operator 100 be left free to bring the cotton bolls into contact with the picking head.

85 2. A cotton picking machine, comprising a receptacle for the cotton, a housing; picking means, means for transferring the cotton from the picking means to the said receptacle, and means for operating the said picking means and transferring means, all within said housing; and means for attaching the said housing rigidly to the body 105 of the operator.

90 3. In a cotton picking machine, the combination with a receptacle for the cotton, a housing; picking means within said housing, means for transferring the cotton from the picking means to the said receptacle and means within said housing for operating the said picking and transferring means, of a carrying strap, a plate rigidly attached to the said housing, a strap to fasten and to hold the said plate rigidly against the body of the operator whereby the direction of the said picker head will be controlled solely by the movement of the body of the operator and his hands be left 110 free to bring the cotton bolls into contact with the said picking means.

115 4. A cotton picking machine having a receptacle for the cotton, a housing; picking means, means for transferring the cot- 120 ton from the picking means to the said receptacle, and means within said housing for operating the said picking and transferring means.

125 5. A cotton picking machine having a receptacle for the cotton, a housing; picking means, means for transferring the cot- 130 ton from the picking means to the said receptacle, and means within said housing for operating the said picking and transferring means.

ton from the said picking means to the said receptacle, and means for operating the said picking means and the said transferring means, all within said housing; and means 5 for attaching the said housing rigidly to the body of an operator whereby the direction of the picking means will be controlled solely by the movements of the body of the operator and his hands be left free to bring 10 the cotton bolls into contact with the said picking means.

5. A cotton picking machine, comprising a receptacle, a motor, an exhaust fan driven by the said motor, a casing for said 15 fan, and a picking head mounted on said fan casing, comprising a housing, two pairs of cooperating brushes, two shafts journaled in the said housing, each carrying and driving two of the said brushes, a 20 worm wheel mounted on each of the said shafts, a worm gear mounted on and operated by an extension of the fan shaft, a cover for the said housing having openings therethrough, over the said brushes, fingers 25 partially closing the said openings, and a stripping comb for each of the said brushes.

6. A cotton picking machine, comprising a receptacle, a motor, an exhaust fan driven by the said motor, a casing for said fan, 30 and a picking head, mounted on the said

fan casing, comprising a housing, two pairs of cooperating brushes, two shafts journaled in the said housing, each carrying and driving two of the said brushes, a worm wheel mounted on each of the said 35 shafts, a worm gear mounted on and operated by an extension of the fan shaft, and a cover for the said housing having openings therethrough, over the said brushes and having fingers partially closing the said 40 openings.

7. A cotton picking machine, comprising a receptacle, a motor, an exhaust fan driven by the said motor, a casing for said fan, and a picking head, mounted on the said 45 fan casing, comprising a housing, two pairs of cooperating brushes, two shafts journaled in the said housing, each carrying and driving two of the said brushes, a worm wheel mounted on each of the said 50 shafts, a worm gear mounted on and operated by an extension of the fan shaft, and a stripping comb for each of the said brushes.

In testimony whereof I have hereunto set 55 my name.

OSCAR B. WINSTON.
